UNITED STATES PATENT OFFICE.

ROBERT J. GIBBON, OF CHICAGO, ILLINOIS, ASSIGNOR TO INTERNATIONAL DEVICE COMPANY, A CORPORATION OF SOUTH DAKOTA.

STARTING DEVICE FOR INTERNAL-COMBUSTION ENGINES.

1,000,595.

Specification of Letters Patent. Patented Aug. 15, 1911.

Application filed August 26, 1908. Serial No. 514,675.

To all whom it may concern:

Be it known that I, ROBERT J. GIBBON, a citizen of the United States, and resident of Chicago, county of Cook, and State of Illinois, have invented certain new and useful Improvements in Starting Devices for Internal-Combustion Engines, of which the following is a specification, and which are illustrated in the accompanying drawings,

10 forming a part thereof.

The invention relates to devices for starting internal combustion engines, and is particularly adapted for use in connection with multi-cylinder engines used with automobiles.

15 The object of the invention is to provide a simple and reliable device for starting such engines, and includes means for selecting the cylinder the piston of which is in such position that the charge may be introduced and immediately fired.

20 It also includes other features as herein-after pointed out, and the invention consists of a structure such as is hereinafter described and as illustrated in the accompanying drawings, in which,—

25 Figure 1 is a detail side elevation of a multi-cylinder gasoline engine applied to a vehicle; Fig. 2 is a detail plan section of a gasoline tank, showing the means for automatically setting the valve mechanism; Fig. 3 is a detail section on the line 3—3 of Fig. 4; Fig. 4 is a vertical, central section through the gasoline tank and valve mechanism; Fig. 5 is a detail perspective, partly in section, of the engine and vehicle starting mechanism; Fig. 6 is a plan section of the tank on the plane of Fig. 2, together with a diagram of the electric connections.

40 There is shown in the drawings a four-cylinder engine, the several cylinders being designated 10, 11, 12 and 13, this engine being mounted immediately forward of the dashboard 14 of an automobile, following

45 common practice. A gasoline tank 15 is mounted in any convenient position, as shown, on the rear face of the dashboard 14, and tubes 16, 17, 18, 19 and 20 lead from this tank to the several cylinders of the engine and to the intake manifold 21, which connects all of the cylinders with a carburetor conventionally shown at 22.

50 A hand-controlled pump is shown at 23 as being located within the tank 15, and dis-

charges to a valve casing 24, also located within or upon the tank.

An air pump 26 is shown as located in the floor of the vehicle in position to be operated by the foot of the operator. This pump delivers through a pipe 27 to the valve casing 24, and with the pump 23 provides means for delivering charges of carbureted air to the engine.

The pump 23 comprises a barrel to which that numeral is applied, and a piston 28 carried by a push rod 29 which extends through a suitable stuffing box 30 at the top of the barrel and is provided with any suitable form of handle 31. A spring 32 coiled about the rod 29 re-acts between a stop plate 33 located within the barrel and a collar 34 fixed upon the stem, and automatically raises the plunger. An intake valve 35 is placed at the bottom of the pump barrel, and the discharge pipe of the pump is shown at 36 and 70 leads to the valve casing 24, this pipe being provided with a check valve conventionally shown at 37. The pump 26 may be of similar construction, and it is not deemed necessary to show the details thereof. In lieu 75 of a handle and pump rod, there is shown a plate 38 of such shape that the foot may be conveniently pressed upon it.

Seated within the casing 24 is a rotative valve 39 having a passage shown as a groove 85 40 in its face, this groove registering continuously with the valve chamber to which the two pumps deliver, and successively with the pipes 16 to 20 which lead from the valve casing. The valve 39 is controlled by a 90 handle 41 mounted upon the valve stem 42. By turning the valve to bring its passage 40 into register with any one of the delivery pipes a charge may, by manipulating the two pumps, be delivered to any one of the 95 engine cylinders or to its intake manifold.

For the purpose of automatically selecting the engine cylinders which should next be fired, there is provided a selector, the case of which is represented at 43, into 100 which leads a shaft 44, which in a four-cycle engine should be driven at one-half the speed of the engine shaft 45. Upon the shaft 44 there is mounted a disk 46 within the casing 43, to which disk there is pivotally attached an arm 47 carrying a contact roller 48, which is forced outwardly against the wall of the casing by means of a spring,

as 49. A plurality of electric terminals, corresponding to the number of cylinders, are fixed in the wall of the casing 43, and designated, respectively, 50, 51, 52 and 53, with 5 which terminals the roller 48 makes contact in succession.

A battery 54 is connected at 55 to the casing 43 and to the disk 46, the other terminal of the battery being connected by means of 10 a wire 56 with a ring 57 located on a plate 58 forming the cover for that part 59 of the tank 15 within which the valve casing 24 is located. The several terminals 50, 51, 52 and 53 are connected by means of wires 60, 15 61, 62 and 63 with terminals 64, 65, 66 and 67 mounted upon and insulated from the plate 58 and arranged within the circle of the ring 57. A solenoid coil 68 is carried by the valve stem 42, its axis being perpendicular thereto. The two ends of the coil 20 terminate in brushes 69 and 70 which engage, respectively, the ring 57 and the terminals 64, 65, 66 and 67, the electric circuit being therefore complete through any one of 25 the terminals 50 to 53 and the corresponding terminals 64 to 67, the solenoid coil, the ring 57 and the line 56.

The core 71 of the solenoid constitutes a 30 latch when brought to central magnetic position by the energizing of the coil, the outer end engaging stop shoulders 72, 73, 74 and 75, formed on an upstanding annular flange 76, rising from the plate 58 and being so located that when engaged by the core they 35 arrest the movement of the valve 39 with its passage 40 in register with one of the delivery pipes 16 to 19, the parts being so arranged that the circuit will be closed in time to advance the core and arrest the valve 40 to bring the pumps into communication with the cylinder next in order of firing.

The inner wall of the flange 76 is so formed as to constitute cams 77, 78, 79 and 80, leading backwardly and inwardly from 45 each of the stop shoulders, so that when the valve is moved backward by hand the solenoid core is forced inward, thus permitting the valve to be turned backward at the will of the operator and permitting him to 50 bring its port 40 into register with the outlet 20 communicating with the intake manifold of the engine.

In order to start the engine, therefore, inasmuch as the roller 48 is always in contact 55 with that terminal of the selector which operates with the engine cylinder next in order of firing, it is only necessary to turn the valve 39 forward until its movement is stopped by the engagement of the solenoid 60 core with one of the shoulders of the flange 76. Both pumps being now operated, the gasoline pump in advance of the air pump, a carbureted charge is forced into this cylinder and may be fired by closing the firing 65 circuit (not shown) in the usual manner.

Preferably before firing, the valve 39 is turned backward to connect the pumps with the manifold, and they are operated for the purpose of throwing a charge into it in order that the cylinder next to draw in its 70 charge shall certainly receive an explosive mixture, which might not be the case if dependence were placed solely on the carburetor 22.

I claim as my invention—

1. In a starter for internal combustion engines having a plurality of cylinders, in combination, a source of fuel supply, communicating passages from such source of supply to the several cylinders, a distributing valve for limiting such communication to a single cylinder, and an electrically-actuated check controlled by the engine for determining the movement of the valve. 75

2. In a starter for internal combustion engines having a plurality of cylinders, in combination, a source of fuel supply, communicating passages from such source of supply to the several cylinders, a distributing valve for limiting such connection to a single cylinder, a solenoid mounted with the valve, an electric circuit, terminals arranged in pairs corresponding in number with the cylinders, stop shoulders in the path of the solenoid core when in magnetic equilibrium, 95 brushes forming terminals of the solenoid coil and arranged to engage the members of the several pairs of named terminals, and a switch actuated by the engine to bring such pairs of contacts successively into the circuit. 100

3. In a starter for internal combustion engines having a plurality of cylinders, in combination, a source of fuel supply, passages connecting such source of supply with the several cylinders, a valve controlling such passages, an electrically-controlled dog for arresting the valve in positions to open such passages successively, and a switch controlled by the engine for actuating the dog 105 in its several positions. 110

4. In a starter for internal combustion engines having a plurality of cylinders, in combination, a source of fuel supply, passages connecting such source of supply with the several cylinders, a valve controlling such passages, and electrically-actuated means controlled by the engine for arresting the valve in positions to open such passages successively. 115

5. In a starter for reciprocating motors 120 having a plurality of cylinders, in combination, passages for fluid leading to the several cylinders, a valve controlling such passages and arranged to open them successively, and electrically-actuated means controlled by the motor for determining the passage to be opened by the valve. 125

6. The combination with an internal combustion engine comprising a plurality of cylinders and an induction manifold common to 130

a plurality of the cylinders, of a tank, passages leading from the tank to the several cylinders, and to the manifold, a valve for controlling such passages, and an electrically-actuated dog controlled by the engine for arresting the valve to open the passages to the cylinders successively.

7. The combination with an internal combustion engine comprising a plurality of cylinders, of fluid passages leading to the several cylinders, a rotatable valve for opening such passages successively, a solenoid

carried by the valve, stop shoulders arranged in the path of the solenoid core when in magnetic equilibrium, cams leading backwardly from such shoulders for forcing the core inward, and means controlled by the engine for closing the circuit of the solenoid as it approaches the shoulders. 15
